Primary Examiner — Leanne Was-Englehart*(74) Attorney, Agent, or Firm* — McCarter & English, LLP(57) **CLAIM**

The ornamental design for an SMT light, as shown and described.

DESCRIPTION

FIG. 1 is a first perspective view of an SMT light showing the top and the left side;

FIG. 2 is a second perspective view of the SMT light of FIG. 1 showing the bottom, the front, and the left side;

FIG. 3 is a front elevational view of the SMT light of FIG. 1;

FIG. 4 is a rear elevational view of the SMT light of FIG. 1.

FIG. 5 is a right side elevational view of the SMT light of FIG. 1, a left side elevational view of the SMT light of FIG. 1 being a mirror image of the right side elevational view; FIG. 6 is a top plan view of the SMT light of FIG. 1; and, FIG. 7 is a bottom plan view of the SMT light of FIG. 1. In the drawings, the broken (phantom) lines depict unclaimed subject matter only and form no part of the claimed design.

1 Claim, 7 Drawing Sheets(56)
